Dr. S. A. Morison

August W. Flarine Inventor
By attorney Prenday M. Barn

UNITED STATES PATENT OFFICE

AUGUST W. FLORINE, OF FORT ATKINSON, WISCONSIN

MAIL-BOX SUPPORT

Application filed May 26, 1928. Serial No. 280,797.

This invention relates in general to supports and more particularly to improved support for rural mail boxes and the like.

While the device of this invention is described and illustrated as employed as a rural mail box support, it will be understood that the device is adapted for other purposes and, therefore, finds a wide field of utility.

The principal object of this invention is to provide in general a support for rural mail boxes and the like, which are generally mounted at a roadside, and to so construct the device that when struck by passing vehicles the container itself will be readily displaced to one side and again returned to normal position without damage to the supporting device or container.

With this end in view the principal objects and advantages of this invention reside in the provision of an improved support, including a displaceable portion and means for maintaining said displaceable portion normally in a predetermined position; the provision in a support of relative movable portions, in combination with means for causing said movable portions to normally take a predetermined position by permitting relative movements of the parts within predetermined limits; the provision of a supporting standard including a stationary base portion and a rotatably displaceable top portion, and means for normally maintaining said portions in predetermined relationship; the provision, in a support for containers, of a supporting standard, a rotatably displaceable arm on the standard and a connection between the arm and standard which causes said arm to normally extend laterally in a predetermined direction, but which permits displacement of said arm through a horizontal plane within predetermined limits; the provision of a supporting device for a mail box or the like including a base standard adapted to be fixed in a desired position along the roadside and including a horizontally displaceable upper portion or supporting arm which is adapted to normally extend toward the roadway, but is provided with means permitting of its temporary displacement away from the roadway; the provision

of a supporting device of the character referred to which is unitary in construction and may be manufactured at low cost and is sturdy, and will withstand the numerous shocks and blows which such devices are subjected to in service.

The foregoing and such other objects and advantages as may appear or be pointed out as this description proceeds are attained in the structure illustrated in the accompanying drawing, in which:

Figure 1 is an elevational view, partly in section, of a device of my invention;

Figure 2 is a fragmentary enlarged elevational view of the joint;

Figure 3 is a longitudinal sectional view taken on the line 3—3 of Figure 2, looking in the direction indicated by the arrows;

Figure 4 is a transverse sectional view taken on the line 4—4 of Figure 2, looking in the direction indicated by the arrows.

Referring now more particularly to the drawing, and first to Figure 1, the device of this invention includes the base standard or supporting post 5, having its lower end suitably fixed in the earth 6 by the provision of a concrete or other base 7.

The standard or post 5 is a tubular member such as a piece of ordinary two inch iron pipe and is provided near its upper end with transverse aligned apertures for receiving a retaining bolt 8 by which the upper portion of the support indicated at 9 may be attached to the base 5.

The upper portion 9 is similarly a length of pipe like the standard 5 and of substantially the same diameter, as will hereafter appear, this upper portion 9 being arched as at 10 and flattened as at 11 to form support for a conventional mail box or the like 12. In the assembly of the parts 5 and 9, the arm 10 is intended to normally project toward a roadway so as to render it convenient for the rural mail carrier to deposit mail in the box 12.

The parts 5 and 9 are relatively rotatably connected so that the mail box and arm 10 may swing in a horizontal plane through substantially 180° in either direction away

from the roadway, in the event that a passing vehicle strikes the mail box.

The connection between the parts 9 and 5 is best shown in Figures 2, 3 and 4, and includes a member 13 affixed to the pipe section 5 by the provision of an auxiliary reinforcing internal pipe section 14, held in a position on the standard 5 by the provision of the bolt 8 hereinabove referred to. The member 13 is riveted or otherwise secured to the inner pipe 14, as indicated at 15, and is angularly internally recessed as at 16 to receive the lower end of the upper section 9, which latter receives the upper part 17 of the auxiliary pipe section 14, so as to form a reinforcing bearing for the rotatable upper part 9.

The upper portion 9 carries a connecting member 18 complementary to the member 13 and riveted or otherwise secured as at 19 to the upper section 9.

The members 13 and 18 are in rotative abutting relation as at 20, the upper member being rotatable upon the shoulder thus formed by the lower member 13.

In order that the member 13 and 18, and, therefore, the members 5 and 9, will assume a normal predetermined position, the cylindrical wall 21 of the member 13 is provided with a substantially V-shaped recess 22 forming opposed camming surfaces 23 and 24, and the opposite outer ends of said camming surfaces terminate in laterally disposed lugs 25 and 26, adjacent the shoulder at the top of the member 13.

The member 18 is complementally provided with a substantially V-shaped tongue 28, which is adapted to engage and seat in the recess 22 and engage and move upwardly along one or the other of the camming surfaces 23 and 24 when the upper portion 9 is rotated. The tongue 28 is provided with a radially projecting lug 29, and, when the portion 9 is rotated from the position shown in Figure 2 to a position 90° in respect thereto in either direction in a horizontal plane, said lug 29 will engage one or the other of the lugs 25 and 26, and thus limit the rotation of said section 9 and the lateral horizontal displacement of the arched arm 10.

Ordinarily, the weight of the mail box and the upper portion 9 are sufficient to return the arm 9 to a position projecting toward the roadway, but as this device is subjected to the elements and as substantially little lubrication is provided, I find it desirable to enhance the action of gravity by supplementing it with a coiled spring 30, which latter has one end secured to a transverse pin 31 in the section 9 and the other end secured to a pin 32 in the inner pipe section 14, and normally exerting a downward pull on the upper section 9.

It will be observed that when the mail box is struck by a passing vehicle or displaced

in any other manner in a horizontal plane, the tongue 28 will ride up on one of the camming surfaces 23 or 24 until the lug 29 abuts one or the other of the lugs 25 or 26. It is necessary to provide these lugs so that the complete rotation of the section 9 cannot take place otherwise the arm 10 would not return to the normal position projecting in the predetermined direction desired.

It will be further observed that for the purpose of adjusting the mail box as to height, the bolt 8 may be removed and the inner pipe 14 raised and the bolt inserted in another opening therein. This may be accomplished without materially weakening the structure.

Having thus described my invention and illustrated its use, what I claim as new and desire to secure by Letters Patent is:

1. In a support, a pair of relatively rotatable axially aligned members adapted to be arranged in a vertical position, a bearing member carried by one of said rotatable members and having a recess therein provided with angularly related cam surfaces, and a second bearing member carried by the other of said axially aligned members and provided with a projecting portion lying in said recess and co-operating with the surfaces thereof whereby upon relative rotation of the axially aligned members, one of the latter will be caused to rise, and stop means for limiting the degree of relative rotative displacement of said axially aligned members, and spring means tending to draw said relative rotatable elements toward each other and to seat said projection in said recess.

2. In a support, a pair of relatively rotatable axially aligned tubular members adapted to be arranged in a vertical position, a bearing member carried by one of said rotatable members and having a recess therein provided with angularly related cam surfaces, and a second bearing member carried by the other of said axially aligned tubular members and provided with a projecting portion lying in said recess and co-operating with the surfaces thereof whereby upon relative rotation of the axially aligned tubular members, one of the latter will be caused to rise, and stop means for limiting the degree of relative rotative displacement of said axially aligned tubular members, and one of said axially aligned tubular members being extended to lie within the other of said members whereby to form a reinforcing bearing therefor.

3. In a support, a pair of relatively rotatable axially aligned tubular members adapted to be arranged in a vertical position, a bearing member carried by one of said rotatable members and having a recess therein provided with angularly related cam surfaces, and a second bearing member carried by the other of said axially aligned tubular members

and provided with a projecting portion lying in said recess and co-operating with the surfaces thereof whereby upon relative rotation of the axially alined tubular members, one of the latter will be caused to rise, stop means for limiting the degree of relative rotative displacement of said axially alined tubular members, said stop means comprising radially disposed lugs on said first mentioned bearing member and a depending lug on said projecting portion and adapted to abut one of said radially disposed lugs, and one of said axially alined tubular members being extended to lie within the other of said members whereby to form a reinforcing bearing therefor.

In testimony whereof, I have hereunto signed my name.

AUGUST W. FLORINE.
